[57] CLAIM

The ornamental design for a liquid dispenser, as shown and described.

DESCRIPTION

FIG. 1 is a perspective view of the liquid dispenser showing my new design;
 FIG. 2 is a side elevational view;
 FIG. 3 is a top plan view;
 FIG. 4 is a front elevational;
 FIG. 5 is a rear elevational view;
 FIG. 6 is a bottom plan view;
 FIG. 7 is a fragmentary view on an enlarged scale of a portion of the liquid dispenser shown in FIG. 4;
 FIG. 8 is a perspective view of a modified form of liquid dispenser showing my new design;
 FIG. 9 is a side elevational view;
 FIG. 10 is a top plan view;
 FIG. 11 is a front elevational;
 FIG. 12 is a rear elevational view;
 FIG. 13 is a bottom plan view;
 FIG. 14 is a perspective view of another modified form of liquid dispenser showing my new design;
 FIG. 15 is a side elevational view;
 FIG. 16 is a top plan view;
 FIG. 17 is a front elevational;
 FIG. 18 is a rear elevational view;
 FIG. 19 is a bottom plan view;
 FIG. 20 is a perspective view of another form of liquid dispenser showing my new design;
 FIG. 21 is a side elevational view;
 FIG. 22 is a top plan view;
 FIG. 23 is a front elevational;
 FIG. 24 is a rear elevational view; and,
 FIG. 25 is a bottom plan view.
